MULTI-PURPOSE SHOE MANUFACTURING MACHINE

Viktor Kremel and Jaroslav Bouchal, Gottwaldov, Czechoslovakia, assignors to Svit, narodni podnik, Gottwaldov, Czechoslovakia

Filed Sept. 20, 1957, Ser. No. 685,320
8 Claims. (Cl. 12—37)

The present invention relates to a multi-purpose shoe manufacturing machine for laying the soles and pressing the shoes on a last, and which has a plurality of working stations arranged circularly in a vertical plane.

Laying the soles and pressing the shoes on a last previously required individual machines of essentially different construction. Whereas laying the soles can be accomplished with a single-pair of press members of relative light weight working at a relatively small working pressure and operated either mechanically or pneumatically, shoe pressing on the last requires a much higher working pressure and a relatively heavier machine.

The previously known sole-laying machines have the disadvantage of a relatively short period of duration of the laying pressure which is indispensable for the reliable bonding of the laid on sole with the shoe bottom. This resulted in the sole coated with glue not having the necessary adhesion to the shoe bottom and thereby getting loose, and causing considerable difficulties during the carrying out of the further operation.

A disadvantage of the existing machine for pressing the shoe on a last and having a single pair of pressing members consisted in its excessively heavy weight, making difficult the transport of the machine. However, the chief disadvantage of this machine lies in the fact that its press bows are susceptible to frequent failures. For this reason, the machine requires considerable maintenance and an extensive supply of spare parts. Consequently, the initial costs and upkeep expenses are considerable.

The present invention has as its object the elimination of the above mentioned disadvantages in that, on the one hand, both the laying of the soles and the pressing of the shoes on a last are carried out on a single machine and, on the other hand, the sole is pressed, during its laying on the shoe, for a much longer period corresponding to the time required for a complete revolution of the working station, so that the loosening of the sole after it has been laid on the shoe cannot occur.

A further feature of the multi-purpose machine according to the present invention is its lower weight and therefore the possibility of more convenient transport thereof, as well as a substantial reduction in the initial costs and upkeep expenses in view of the novel design of the press bows provided on the machine.

The essential feature of the present invention consists in that each of the working stations of the machine has a pressing cushion housing on which a press bow, having an inverted U-shape, is pivotally arranged, the fully open and hollow part of said bow being suitable for the suspension therein of a support, while said hollow part of the bow terminates in lever-like ends.

The above, and other objects, features and advantages of the present invention will be apparent in the following detailed description of an illustrative embodiment thereof illustrated in the accompanying drawings, wherein

FIG. 1 shows a front view of the machine with the working stations and circular carrier, the switching off device being provided at the front of the machine,

FIG. 2 is a side view of the upper part of a working station with the press bow shown in section and the shoe in pressing position, and

2

FIG. 3 is a detail sectional view along the line A—A of FIG. 2.

Referring now to the drawings, it will be seen that the machine embodying the invention includes a welded drum 1 mounted on a shaft 60 which is supported in the machine frame comprising a front wall 4 (FIG. 1) and a rear wall 5 (FIG. 2). The drum is provided with lugs 2, 3 which support a pressing housing 6, the number of said pressing cushion housings corresponding to the number of pressing stations which are circularly arranged in the machine in a vertical plane. In each pressing cushion housing 6 there is mounted on a pivot 7 a press bow 8 having an inverted U-shaped main part 9 with lever-like portions 17 and 18 at the opposite ends thereof. As shown in FIG. 3, the main part 9 of bow 8 has an inverted U-shaped cross-section with outwardly directed stiffening flanges along the lower edges.

A support 10 is suspended within the part 9 of the bow 8 on pivot 11. Mounted in a part of this support 10 are racks 12, 13 which are adjustable in height in opposite directions by equal amounts through movement about a centrally arranged pinion 16.

Pressure members 14 and 15 with cushions 21 are arranged at the bottom end of the racks 12 and 13, and 25 are slidable perpendicularly to the axis of the racks. The racks 12, 13 together with the pressure members 14, 15 are arranged perpendicularly with respect to the contacted parts of the surface of the frontal shoepoint and shaft part of shoe B and can be adjusted in the 30 direction of the displacement of the pinion 16. The angular displacement of the support 10 about the pivot 11 is adjustable by means of a screw 20 and is counterbalanced by a spring 29.

The end of the support 10 remote from pinion 16 35 has a chamfered end piece 22 on which a rear pressure member 19 is horizontally adjustably mounted (FIG. 2) for acting upon the heel part of the shoe B. In view of the fact that the press bow 8 is hollow, it can fulfil any requirements as to mechanical strength and at the 40 same time utilize to the fullest extent the available space for the action of the support 10 together with the racks 12, 13 and pressure members 14, 15, thus permitting reduction of the machine's dimensions and weight and providing a more advantageous working level and the 45 possibility of clear supervision of the working space.

Each press bow 8 is provided with a guide slot 23 50 slidably receiving the end of an arm 24 mounted turnably on a pivot 26. A pawl 27 is also supported on pivot 26 for co-operation with the leverlike end 17 of the 55 press bow 8 which has ratchet teeth thereon. The said pawl 27 is urged into engagement with the ratchet teeth by a spring not illustrated in the drawing and is provided with an actuating handle 37 for use in case of malfunctioning of the machine to permit disengagement of the pawl 27 from the ratchet teeth.

A circular carrier 30 (FIGS. 1 and 2) is fixed to front 60 wall 4 by bolts 31, and carries a pawl releasing device 32 in a position ahead of the vertical position of the working stations (FIG. 1). This device consists of a cam member 33 with a chamfered abutment face 34 at one end and mounted on a pivot 37 at that one end, while the opposite end of the cam member is supported by a spring 36.

In order to rotate the drum 1 with the several working stations thereon, the machine may further include an electric motor E (FIG. 1) having a pulley 51 secured on its shaft and driving belts 58 which also run over a pulley 52 for rotating the latter. The pulley 52 is mounted on a drive shaft 57 and is releasably coupled to the latter by a clutch 50 so that drive shaft 57 is rotated only when clutch 50 is engaged. Rotation of shaft 57 is trans-

mitted to drum 1 by means of a worm 54 on shaft 57 meshing with a worm gear 55 which is secured to the drum.

The clutch 50 is actuated by a rockable lever 53 which, at its free upper end, is coupled to a shaft 46 which is axially movable and also turnable about its axis. The shaft 46 carries a latch 47 projecting radially therefrom and movable, in response to turning of shaft 46, between an operative position (FIG. 1), in which latch 47 projects into the path of movement of a circularly arranged series of stop pins 59 projecting from gear 55, and a released position in which latch 47 is withdrawn from the path of pins 59.

In order to operate the latch 47 there is provided a treadle 45 which is rockably mounted at the bottom of the machine frame and which is connected to a lever 44. A rod 49 extends from lever 44 to a radial arm at one end of shaft 46 and a spring 43 is connected to treadle 45 to raise the latter and thereby cause turning of shaft 46 in the direction moving latch 47 to its operative position. However, when treadle 45 is depressed, latch 47 is moved to its released position. A spring (not shown) is provided for urging shaft 46 axially in the direction for causing the lever 53 to engage clutch 50, while the engagement of one of the stop pins 59 with the latch 47 during rotation of drum 1 causes axial movement of shaft 46 in the opposite direction for disengaging the clutch 50. The number of stop pins 59 is equal to the number of working stations on drum 1 so that, if the treadle 45 is depressed to release latch 47 and, thereafter, the treadle is freed to permit return of latch 47 to its operative position, the drum 1 will turn through an angle α which is equal to the angular spacing between the successive working stations on the drum.

The sole-laying and shoe-pressing machine according to the present invention as above described operates in the following manner:

With the working station S (FIGS. 1 and 2) being in an inactive position, i.e. with the pressbow 8 swung outwards about the pivot 7 until the upper end of the arm 24 seats against an elastic insert 38 in the guide slot 23 (FIG. 2), the shoe B is introduced laterally into the pressing cushion housing 6. Thereupon the piston 41 of the cylinder 28 is displaced by compressed air or hydraulic fluid so as to effect the pressing-on closing movement of the press bow 8 through the medium of a double-armed lever 25. With the cushions 21 on the racks 12, 13 adjusted in advance to the height corresponding to the respective shoe size and with the front pressure members 14, 15 and rear pressure member 19 on the shoe, the ratchet teeth of the end 17 of bow 8 come into contact with the pawl 27 and the bow is secured. Then the drum 1 (FIGS. 1 and 2) is rotated, as described above, and during such rotation, a part of pawl 27 rides on the chamfered face 34 of the cam member 33, and is thereby automatically swung outwards for disengagement from the ratchet teeth on the end 17 of bow 8. Upon such release of pawl 27 from the end 17 of the press bow 8, the latter is turned upwards about the pivot 7 through the force of a spring 39 connected to the end 18 of bow 8, and the double-armed lever 25 is pressed away by the upward turning of bow 8. With this opening movement of the press bow 8 the support 10 together with the front-pressure members 14, 15 and the rear pressure member 19 are lifted, whereupon the released shoe is removed sideways and another shoe can be inserted to repeat the operating cycle.

An outstanding advantage of the machine according to the present invention consists in the novel arrangement of the support 10 inside the hollow press bow 8 whereby it is possible to put on the sole within the small space provided between the pressure members 14, 15 and 19 and the pressing cushion housing and to press the sole shape of the welt-stitched shoe which is stretched advantageously on a last. The apparatus is suitable for

all men's and ladies' sizes. Thus, the productivity of the labour and the quality of the shoes produced are substantially improved and the weight of the machine as well as its initial cost and upkeep expenses are greatly reduced.

We claim:

1. In a sole laying and shoe pressing machine, in combination, a frame; drum means rotatable on said frame about an axis; a plurality of pressing cushion housings arranged on said drum about said axis; a plurality of elongated arcuate press bows, each having one longitudinal end portion pivotally secured to a corresponding one of said housings for movement of the other longitudinal end portion of said press bow between respective positions thereof adjacent and remote from the corresponding housings, and a main portion intermediate said end portions, said main portion being spaced from said housing and of U-shaped cross section so as to define a cavity therein having an open side opposite said housing; a support member pivotally mounted in said cavity; a plurality of pressure members mounted on said support member and projecting therefrom toward said housing for clamping a shoe between said pressure members and said housing; fluid-actuated pressure means mounted on said frame and alignable with said press bows by rotation of said drum means for sequentially moving said press bows from said remote toward said adjacent positions of said other end portion thereof; stop means on each of said press bows and on the corresponding housing for retaining said press bows in the respective adjacent position of said other end portion thereof; and release means mounted on said frame for sequentially engaging said stop means during rotation of said drum means for releasing said press bows from said adjacent position of said other end portion thereof.

2. In a sole laying and shoe pressing machine, in combination, a frame; drum means rotatable on said frame about an axis; a plurality of pressing cushion housings arranged on said drum about said axis; a plurality of elongated arcuate press bows, each having one longitudinal end portion pivotally secured to a corresponding one of said housings for movement of the other longitudinal end portion of said press bow between respective positions thereof adjacent and remote from the corresponding housing, and a main portion intermediate said end portions, said main portion being spaced from said housing and of U-shaped cross section so as to define a cavity therein having an open side opposite said housing; a support member pivotally mounted in said cavity; a plurality of pressure members mounted on said support member and projecting therefrom toward said housing for clamping a shoe between said pressure members and said housing; stop means on each of said press bows and on the corresponding housing for retaining said press bows in the respective adjacent positions of said other end portions thereof; and releasing means mounted on said frame for sequentially engaging said stop means during rotation of said drum means for releasing said press bows from said adjacent position of said other end portions thereof.

3. In a sole laying and shoe pressing machine, in combination, a frame; drum means rotatable on said frame about an axis; a plurality of pressing cushion housings arranged on said drum about said axis; a plurality of elongated arcuate press bows, each having one longitudinal end portion pivotally secured to a corresponding one of said housings for movement of the other longitudinal end portion of said press bow between respective positions thereof adjacent and remote from the corresponding housing, and a main portion intermediate said end portions, said main portion being spaced from said housing and of U-shaped cross section so as to define a cavity therein having an open side opposite said housing; a support member pivotally mounted in said cavity; a plurality of pressure members mounted on said support member and projecting therefrom toward said

housing for clamping a shoe between said pressure members and said housing; first stop means on each of said press bows and on the corresponding housing for retaining said press bows in the respective adjacent position of said other end portion thereof; second stop means on each of said press bows and on the corresponding housing for limiting movement of said press bow from said adjacent toward said remote position of said other end portion thereof; and releasing means mounted on said frame for sequentially engaging said stop means during 10 rotation of said drum means for releasing said press bows from said adjacent position of said other end portions thereof.

4. In a sole laying and shoe pressing machine, in combination, a frame; drum means rotatable on said frame about an axis; a plurality of pressing cushion housings arranged on said drum about said axis; a plurality of elongated arcuate press bows, each having one longitudinal end portion pivotally secured to a corresponding one of said housings for movement of the other longitudinal end portion of said press bow between respective positions thereof adjacent and remote from the corresponding housing, and a main portion intermediate said end portions, said main portion being spaced from said housing and of U-shaped cross section so as to define a cavity therein having an open side opposite said housing; an elongated support member having two end portions and a central portion pivotally mounted in said cavity; a plurality of pressure members mounted on said support member and projecting therefrom toward said housing for clamping a shoe between said pressure members and said housing, at least one of said pressure members being mounted on each of said end portions of said support member; stop means on each of said press bows and on the corresponding housing for retaining said press bows in the respective adjacent position of said other end portion thereof; and releasing means mounted on said frame for sequentially engaging said stop means during rotation of said drum means for releasing said press bows from said adjacent position of said other end portions thereof.

5. In a sole laying and shoe pressing machine, in combination, a frame; drum means rotatable on said frame about an axis; a plurality of pressing cushion housings arranged on said drum about said axis; a plurality of elongated arcuate press bows, each having one longitudinal end portion pivotally secured to a corresponding one of said housings for movement of the other longitudinal end portion of said press bow between respective positions thereof adjacent and remote from the corresponding housing, and a main portion intermediate said end portions, said main portion being spaced from said housing and of U-shaped cross section so as to define a cavity therein having an open side opposite said housing; an elongated support member having two end portions and a central portion pivotally mounted in said cavity; a plurality of pressure members mounted on said support member and projecting therefrom toward said housing for clamping a shoe between said pressure members and said housing, one of said pressure members being mounted on one of said end portions of said support member and two pressure members being movably mounted on the other end portion; a pinion on said support member; rack means on each of said two pressure members meshing with said pinion for enforced movement of one of said two pressure members in substantially the opposite direction from the direction of movement of the other one of said two pressure members; stop means on each of said press bows and on the corresponding housing for retaining said press bows in the respective adjacent position of said other end portion thereof; and releasing means mounted on said frame for sequentially engaging said stop means during rotation of said drum means for releasing said press bows from said adjacent position of said other end portions thereof.

5. In a sole laying and shoe pressing machine, in combination, a frame; drum means rotatable on said frame about an axis; a plurality of pressing cushion housings arranged on said drum about said axis; a plurality of elongated arcuate press bows, each having one longitudinal end portion pivotally secured to a corresponding one of said housings for movement of the other longitudinal end portion of said press bow between respective positions thereof adjacent and remote from the corresponding housing, and a main portion intermediate said end portions, said main portion being spaced from said housing and of U-shaped cross section so as to define a cavity therein having an open side opposite said housing; a support member pivotally mounted in said cavity; a plurality of pressure members mounted on said support member and projecting therefrom toward said housing for clamping a shoe between said pressure members and said housing; stop means on each of said press bows and on the corresponding housing for retaining said press bows in the respective adjacent position of said other end portion thereof, said stop means having an abutment face; and releasing cam means mounted on said frame for sequentially engaging said abutment faces of said stop means during rotation of said drum means for releasing said press bows from said adjacent position of said other end portions thereof.

7. In a sole laying and shoe pressing machine, in combination, a frame; drum means rotatable on said frame about an axis; a plurality of pressing cushion housings arranged on said drum about said axis; a plurality of elongated arcuate press bows, each having one longitudinal end portion pivotally secured to a corresponding one of said housings for movement of the other longitudinal end portion of said press bow between respective positions thereof adjacent and remote from the corresponding housing, and a main portion intermediate said end portions, said main portion being spaced from said housing and of U-shaped cross section so as to define a cavity therein having an open side opposite said housing; a support member pivotally mounted in said cavity; a plurality of pressure members mounted on said support member and projecting therefrom toward said housing for clamping a shoe between said pressure members and said housing; ratchet-and-pawl means respectively mounted on each of said press bows and on the corresponding housing for retaining said press bows in the respective adjacent position of said other end portion thereof; and releasing means mounted on said frame for sequentially engaging said ratchet-and-pawl means during rotation of said drum means for releasing said press bows from said adjacent position of said other end portions thereof.

8. In a sole laying and shoe pressing machine, in combination, a frame; drum means rotatable on said frame about an axis; a plurality of pressing cushion housings arranged on said drum about said axis; a plurality of elongated arcuate press bows, each having one longitudinal end portion pivotally secured to a corresponding one of said housings for movement of the other longitudinal end portion of said press bow between respective positions thereof adjacent and remote from the corresponding housing, and a main portion intermediate said end portions, said main portion being spaced from said housing and of U-shaped cross section so as to define a cavity therein having an open side opposite said housing; an elongated support member having two end portions and a central portion pivotally mounted in said cavity; a plurality of pressure members mounted on said support member and projecting therefrom toward said housing for clamping a shoe between said pressure members and said housing, one of said pressure members being mounted on one of said end portions of said support member, and two pressure members being movably mounted on the other end portion; a pinion on said support member; rack means on each of said two pressure members meshing with said pinion for enforced movement of one of said two pressure members in substantially the opposite direction from the direction of movement of the other one of said two pressure members; stop means on each of said press bows and on the corresponding housing for retaining said press bows in the respective adjacent position of said other end portion thereof; and releasing means mounted on said frame for sequentially engaging said stop means during rotation of said drum means for releasing said press bows from said adjacent position of said other end portions thereof.

two pressure members in substantially the opposite direction from the direction of movement of the other one of said two pressure members; fluid-pressure-actuated pressure means mounted on said frame and alignable with said press bows by rotation of said drum means for sequentially moving said press bows from said remote toward said adjacent position of said other end portion thereof; ratchet-and-pawl means respectively mounted on each of said press bows and on the corresponding housing for retaining said press bows in the respective adjacent positions of said other end portions thereof; stop means on each one of said press bows and on the corresponding housing for limiting movement of said press bow from said adjacent toward said remote position of said other end portion thereof; an abutment face on each of said ratchet-and-pawl means; and releasing cam means mounted on said frame for sequentially engaging said

abutment faces during rotation of said drum means for releasing said press bows from said adjacent position of said other end portions thereof.
